3,144,161 BASKETS OF WIRE AND SHEET METAL CONSTRUCTION

Clarence S. Glenny, deceased, late of Rockford, Ill., by
Margaret Glenny, administratrix, Rockford, Ill., as
signor to The Washburn Company, Worcester, Mass.,
a corporation of Massachusetts

Filed Aug. 23, 1961, Ser. No. 135,704
2 Claims. (Cl. 220—19)

This invention relates to a new and improved combination wire and sheet metal basket construction especially designed with a view to solving the problems of locker baskets, which require that sufficient openings be provided for good ventilation of the contents while still preventing, or at least greatly reducing, pilferage.

In the earlier Patent 1,722,416, there was disclosed a wire basket construction incorporating sheet metal corner pieces bent to right angle form to reinforce the corners and discourage pilfering, but with so much of the contents of the basket exposed to view at the end between the sheet metal corner pieces, there was too much danger of the wires being cut and bent to provide large enough openings through which the contents of the basket could be removed. It is, therefore, the principal object of my present invention to provide sheet metal end walls having inwardly bent flanges on opposite sides to completely conceal the end portions of the wire side walls and bottom wall, these wire portions having right angle bent ends welded by projection welding onto ribs pressed inwardly from the sheet metal of the end walls at both sides and across the bottom portion and extending in transverse relationship to the right angle bent ends of the wires, making a very strong end construction designed to positively discourage pilfering. The right angle bent ends of the wires, when welded to the sheet metal end pieces on the ribs lie substantially flush against the inner sides of these end pieces and are not, therefore, apt to catch onto articles put in the basket. Circular vent holes provided in the sheet metal end walls have their edges outwardly embossed to avoid cutting or abrading articles placed in the basket that might otherwise be subject to damage in those ways while also improving the outside appearance of the basket. The points where the projection welds occur are also marked by uniformly spaced flattenings of the impressed ribs and that adds to the attractive appearance of the basket, or at least does not detract therefrom, and there being nothing to invite efforts to cut and bend so as to enlarge an opening, as was true with the old design, this new basket construction is substantially pilfer-proof.

For further protection against pilfering, the sheet metal front wall may have the top portion thereof bent horizontally inwardly, and this inwardly bent top portion is fastened at its opposite ends to the top frame by curling the portions around the frame and, if need be, welding the same thereto.

The invention is illustrated in the accompanying drawings, in which—

FIG. 1 is a perspective view of a locker basket made in accordance with my invention;

FIGS. 2 and 3 are vertical sections through the front and rear ends of the basket with intermediate portions of each section broken away to conserve space and enable showing the parts on a larger scale;

FIGS. 4 and 5 are sectional details on the lines 4—4 or 5—5 of FIGS. 2 and 3, respectively;

FIG. 6 is a perspective view of another locker basket similar to that in FIG. 1 but including an inwardly bent top portion on the front wall for further protection against pilferage; and

2

FIGS. 7 and 8 are vertical sections through the front and rear end portions of the basket of FIG. 6 with intermediate portions in each section broken away to conserve space and enable showing the parts on a larger scale.

Similar reference numerals are applied to corresponding parts throughout the views.

Referring to the drawings and first of all to FIGS. 1 to 5, the invention is shown embodied in a locker basket indicated generally by the reference numeral 10, this being of the kind used around gymnasiums. Such baskets receive rough handling and when not reinforced properly, some fall apart and are unfit for further use, and, as pointed out above, when such baskets are not constructed to prevent the spreading apart of the wires, they are apt to be broken into and the contents pilfered. The basket 10, in accordance with my invention, has a sheet metal front wall 11 and a sheet metal rear wall 12 but is otherwise of wire construction in the side walls 13 and 14 and bottom wall 15, the sheet metal ends 11 and 12 being of identical form except for the gap 16 at the middle of the upper end for extension of the eyelet or loop 17 provided at the middle of the front end of the heavy wire top frame 18. Both of the sheet metal pieces 11 and 12 have inwardly bent side flanges 19 on the opposite sides thereof and an inwardly bent flange 20 at the bottom, and the ends of the side walls 13 and 14 and the bottom wall 15 are enclosed by these three flanges, so that when the basket 10 is disposed in its compartment in a locker, the front end portions of the horizontal wires 21 in the side walls 13 and 14 are not usually visible, even if the locker basket is pulled as far forward as the loop 17 will permit, and the same is true of the horizontal wires 22 in the bottom wall 15. Consequently, even if a would-be thief managed to get the basket pulled out far enough from its compartment to expose the end portions of the wires 21 and 22, the small space left to the rear of the flanges 19 and 20 for working on the wires to spread them apart would make the work too difficult and the space would not be wide enough to permit removal of articles from the basket even if the flanges 19 and 20 were bent out of the way to some extent. The wires 21 have laterally bent right angle end portions 23 and the wires 22 have upwardly bent end portions 24, and all of these end portions are welded to the sheet metal end pieces 11 and 12 by projection welding, the end pieces having vertical inwardly impressed ribs 25 parallel to the flanges 19, extending in a transverse relationship to the bent ends 23 and welded thereto at the points of intersection as indicated at 26, and a horizontally extending inwardly impressed rib 27 parallel to the bottom flange 20 extending in transverse relationship to the upwardly bent ends 24 and welded thereto at the points of intersection as indicated at 28, whereby to make both ends of the basket extremely sturdy and rigid so as to withstand the roughest handling and also discourage pilfering. Ventilation holes 29 are provided in ample number in the end pieces 11 and 12 to insure good ventilation, but all of these circular holes are small enough and spaced apart far enough to discourage breaking into the basket, and it will be noticed that each of these openings is defined by an outwardly bent frusto-conical flange 30 for reinforcement, the outward bending or swaging of these flanges eliminating rough projections on the inner side and thereby eliminating likelihood of articles placed in the basket being scuffed or cut by contact with these portions. The bent ends 23 and 24 of the wires 21 and 22, when welded to the end pieces 11 and 12, have their extremities in close abutment with the end pieces as indicated at 31, so that there is no likelihood of any articles placed in the basket getting snagged thereon,

especially since these portions 23 and 24 are so close to the corners of the basket. The upper ends of the end pieces 11 and 12 are curled around the opposite ends of the rectangular wire top frame 18, as indicated at 32, and are suitably welded thereto to give further assurance against pilfering. The abutting ends of the wire of frame 18 are indicated at 33 in FIG. 1 and, hence, when the rear wall 12 is curled around and welded to the rear portion of the frame 18, there is no danger of these ends of the wire frame being spread apart. The inward offsetting of the L-shaped end portions 34 of the wires 21 and the upward offsetting of the L-shaped end portions 35 of the wires 22 is just enough to make the flanges 19 lie flush with the outer sides of the side walls 13 and 14 and make the bottom flange 20 lie substantially flush with the underside of the bottom wall 15, thereby eliminating scuffing of the edges of the flanges 19 and 20 on the locker compartment and eliminating wear and tear generally on anything that the basket is apt to come in contact with while in service.

The wire basket indicated generally by the reference numeral 10' in FIGS. 6 to 8 is similar to the basket 10 just described, and corresponding parts have been numbered alike, but the sheet metal front piece 11' in this basket has a channel 36 formed transversely of its upper end in which the front end of the heavy wire top frame 18 is entered and suitably welded, and there is a rearwardly extending top wall 37 defined as an extension of one side of the channel 36 to cover the top of the basket at the front end far enough inwardly from the front end to eliminate any likelihood of pilfering in the event the basket fits rather loosely in its compartment in the locker, the channel 36 and top wall 37 being notched out as indicated at 16' in FIG. 6 to accommodate the loop 17 similarly as in the other construction. The top wall 37 has its opposite ends curled around the side portions of the top frame 18 as indicated at 38 and suitably welded thereto to eliminate any likelihood of a would-be thief prying this top wall upwardly with respect to the top frame 18 and thereby gaining access to the inside of the basket at the front end. Any opening that might be enlarged in this fashion would not be large enough to enable removal of anything from the basket.

It is believed the foregoing description conveys a good understanding of the objects and advantages of the invention. The appended claims have been drawn to cover all legitimate modifications and adaptations.

What is claimed is:

1. A generally rectangular basket having opposed substantially vertical sheet metal end walls, a horizontal bottom wall of wire construction and opposed upwardly bent side walls of wire construction integral therewith, said wire walls including longitudinally extending wires that are disposed horizontally in the bottom and side walls, and transversely extending wires that are disposed vertically in the side walls, and a generally rectangular horizontal wire top frame, the opposed ends of which have the upper ends of the sheet metal end walls secured thereto, and the opposed sides of which have the upper ends of vertically extending wires of said side walls secured thereto, said sheet metal end walls having flanges bent inwardly substantially at right angles thereto on the bottom and side edges thereof for reinforcement and also to provide attaching portions that are secured in abutment with the outer side of the end portions of the horizontally extending wires of the bottom and side walls,

these end portions being bent into inwardly offset relation to the bottom and side walls enough to make the outer surfaces of said flanges flush with the outside of the bottom and side walls for smooth non-snag sliding of the basket, and these end portions also having their ends bent substantially at right angles and secured in abutment with the inner side of marginal portions of said sheet metal end walls adjacent said flanges, the said marginal portions of said end walls being offset outwardly enough to make the inner side of said end walls adjacent said marginal portions flush with the right angle bent ends of the wires to provide relatively smooth inner surfaces on said end walls despite the right angle bent ends of the end portions of said horizontal wires.

2. A generally rectangular locker basket having opposed substantially vertical sheet metal front and back walls, a horizontal bottom wall of wire construction and opposed upwardly bent side walls of wire construction integral therewith, said wire walls including longitudinally extending wires that are disposed horizontally in the bottom and side walls, and transversely extending wires that are disposed vertically in the side walls, and a generally rectangular horizontal wire top frame, the rear end of which has the upper end of the sheet metal back wall secured thereto, the sheet metal front wall having its upper end bent rearwardly substantially at right angles and projecting over and in contact with the front end of said wire top frame to cover a substantial portion of the front end of the basket for protection of the basket contents against theft, this inwardly bent portion having lateral edge portions looped around and secured to the side portions of the wire top frame, the upper ends of the vertically extending wires of said side walls being also secured to the side portions of said wire top frame, said sheet metal end walls having flanges bent inwardly substantially at right angles thereto on the bottom and side edges thereof for reinforcement and also to provide attaching portions that are secured in abutment with the outer side of the end portions of the horizontally extending wires of the bottom and side walls, these end portions being bent into inwardly offset relation to the bottom and side walls enough to make the outer surfaces of said flanges flush with the outside of the bottom and side walls for smooth non-snag sliding of the basket, and these end portions also having their ends bent substantially at right angles and secured in abutment with the inner side of marginal portions of said sheet metal end walls adjacent said flanges, the said marginal portions of said end walls being offset outwardly enough to make the inner side of said end walls adjacent said marginal portions flush with the right angle bent ends of the wires to provide relatively smooth inner surfaces on said end walls despite the right angle bent ends of the end portions of said horizontal wires.
